UNITED STATES PATENT OFFICE.

IRA H. GRIFFITHS, OF SYRACUSE, NEW YORK.

DENTAL-POWDER CONTAINER AND FEEDER.

1,289,446.

Specification of Letters Patent. Patented Dec. 31, 1918.

Application filed March 21, 1917. Serial No. 156,429.

To all whom it may concern:

Be it known that I, IRA H. GRIFFITHS, a citizen of the United States of America, and resident of Syracuse, in the county of 5 Onondaga, in the State of New York, have invented new and useful Improvements in Dental-Powder Containers and Feeders, of which the following, taken in connection with the accompanying drawings, is a full, 10 clear, and exact description.

This invention relates to certain improvements in a dental powder container and feeder for supplying powder to a tooth brush.

15 The objects are as follows:—

First, to provide a simple, compact and comparatively inexpensive device which may be carried in a relatively small space, and at the same time constituting a substantially 20 air and moisture-tight receptacle for the retention of a limited quantity of powder.

Second, to enable the powder to be fed to the brush in relatively small quantities without liability of waste or excessive supply.

25 Third, to utilize the feeding device as a means for cutting off the supply of powder to the brush when restored to its normal closed position.

Fourth, to utilize a portion of the same 30 feeding means for agitating or preventing caking of the powder in the receptacle.

Fifth, to provide the feeding device with a laterally projecting abutment adapted to be engaged by the handle or shank of the 35 brush to prevent contact of the brush with the feeding stem, thereby obviating the liability of moistening said stem and transmitting said moistures to the powder within the receptacle.

40 Other objects and uses will be brought out in the following description.

In the drawings—

Figure 1 is a perspective view of my invention showing the feeding rod as extended. 45 Fig. 2 is an enlarged longitudinal sectional view of the device showing the feeding rod in its normal or closed position.

Fig. 3 is a sectional view similar to Fig. 2, except that the feeding rod is shown in 50 elevation and extended for use, and also showing the tooth brush in position for receiving the powder from the feeding rod.

Fig. 4 is a transverse sectional view taken in the plane of line 4—4, Fig. 2.

This device comprises a cylindrical tube 55 —1— having end heads —2— and —3— normally closing the open ends thereof and together with the tubular body —1— constitutes a receptacle or container for a quantity of powder, as —a—.

60 One of the end heads, as —2—, may be permanently or rigidly secured to the corresponding end of the tube —1—, while the opposite end head, as —3—, may be removable and held in place by friction or 65 by any other well-known form of fastening means, not necessary to herein illustrate or describe.

The head —3— is provided near one side with an opening in which is tightly fitted 70 a tubular sleeve or gland —4— which projects a short distance into the tube —1— to reduce the liability of leakage of the powder therethrough when the container is inverted or placed in a horizontal position, or rather 75 when the head —2— is tilted below that of the head —3—.

This sleeve or gland —4— also constitutes a guide for a longitudinally movable 80 powder-feeding rod —5— which is sufficiently long to extend the entire length of the interior of the tube —1— and to protrude at one end a short distance through and beyond the outer end of the sleeve or gland —4—.

85 The rod —5— is preferably cylindrical and is provided at its inner end with a radially projecting agitator blade —6— extending diametrically of the container tube —1— and serving as a means for agitating 90 or loosening the powder in said tube as the rod —5— is moved backward or forward or rocked upon its axis.

The outer end of the feeding rod —5— is also provided with a radially projecting arm 95 —7—, the free end of which, as —8—, constitutes an abutment against which the handle or shank —b— of a tooth brush —B— is adapted to abut during the operation of supplying the powder to the bristles of said 100 brush in a manner presently described.

The length of the arm —7— is somewhat greater than that of the bristles of the brush —B— so as to prevent contact of the brush with the feeding rod —5—, as shown more 105 clearly in Fig. 3, the purpose being to prevent transmission of moisture from the brush to the rod and thence from the rod

to the powder within the container —1—, which, of course, would tend to cake the powder and prevent its free exit by the withdrawal of the feeding rod.

5 The outer end of the rod —5— is also provided with a limiting stop or cap portion —9— which fits over and upon the outer end of the sleeve or gland —4— when the feeding rod is closed or forced into the tube —1—, the agitator blade —6— also serving as a limiting stop coöperating with the inner end of the sleeve or gland —4— to limit the outer movement of the rod —5—.

10 The intermediate portion of the feeding rod —5— is provided with a series of indentations or recesses —10— in spaced relation forming pockets in which the powder is adapted to collect when registered with the interior of the tube —1—, or when the 15 rod is forced inwardly to the limit of its movement.

15 These indentations or pockets —10— are preferably formed in the same side of the rod as that from which the arms —6— and 20 —7— project and, therefore, the arm —7— serves as an indicator to determine the position of the pockets, and the arms also act as weights to turn the rod so that the pockets will be at the under side when the tube —1— 25 is held in the hand with the rod at the top, as shown in Fig. 3, the device being usually 30 turned to this position when it is desired to deposit powder upon the tooth brush.

35 The series of indentations or pockets —10— terminate a distance from the opposite ends of the rod corresponding to the length of the sleeve —4— so that when the rod is forced to either of its extreme inward or outward positions, the cylindrical end 40 portions thereof will substantially fill the space within the tube —4— and thereby serve as valves —11— for effectively closing the outlet through said sleeve, and thus preventing the accidental escape of powder 45 when the rod is in either extreme position of adjustment.

50 The agitator blade —6— also serves to limit the rocking movement of the feeding rod —5— so that the indentations or pockets —10— will always face the axis or center of the tube.

55 In operation, when it is desired to supply a limited quantity of powder to the brush —B—, the container is usually inverted to the position shown in Fig. 2 with the feeding

rod —5— at the bottom which allows the powder to enter the pockets —10—.

Then by withdrawing the rod outwardly from its normal closed position, it is evident that the powder in the pockets will also be 60 drawn outwardly through the sleeve or gland —4— which serves to cut off any excess powder which may lodge on the feeding rod at the outside of the pockets, and also to pack the powder more or less firmly 65 in said pockets.

Either before or during this withdrawal of the feeding rod —5—, the container may be restored to the position shown in Fig. 3, and the brush —B— may be placed in position to receive the powder from the pockets 70 —10—, as shown in the same figure, with its shank —b— resting against the abutment —8—.

75 If the powder tends to adhere to the walls of the pockets, the shank of the brush may be tapped against the abutment —8— with sufficient force to jar the feeding rod —5— and thereby loosen the powder therefrom, allowing it to deposit upon the bristles of the 80 brush at different points throughout its length, it being understood that the length of the series of pockets —10— is approximately, or slightly less than that of the brush so as to avoid waste of the powder. 85

As soon as the powder is deposited upon the brush from the feeding rod, the latter may be restored to its normal position ready for a repetition of the operation previously described when necessary. 90

What I claim is:

In a device of the character described, the combination of a tubular container having a guide opening in one end, a feeding rod movable endwise in said guide and provided 95 with a plurality of pockets in one side, said pockets being movable with the rod into and out of the container, the outer end of the rod being provided with a laterally projecting arm having an abutment for engagement 100 by the shank of a tooth brush to prevent contact of the bristles of the brush with the feeding rod.

In witness whereof I have hereunto set my hand this 17 day of March, 1917.

IRA H. GRIFFITHS.

Witnesses:

HOWARD P. DENISEN,
M. VIOLA HOWLAND.
